UNITED STATES PATENT OFFICE.

HERMAN S. HEICHERT, OF PITTSBURGH, AND HARRY S. DRURY, OF FORD CITY, PENNSYLVANIA, ASSIGNORS TO PITTSBURGH PLATE GLASS COMPANY, OF PITTSBURGH, PENNSYLVANIA, A CORPORATION OF PENNSYLVANIA.

LEER.

1,126,465.

Specification of Letters Patent.

Patented Jan. 26, 1915.

Application filed January 23, 1914. Serial No. 813,900.

To all whom it may concern:

Be it known that we, HERMAN S. HEICHERT, of Pittsburgh, Allegheny county, Pennsylvania, and HARRY S. DRURY, of 5 Ford City, in the county of Armstrong and State of Pennsylvania, have invented certain new and useful Improvements in Leers, of which the following is a specification.

The invention relates to leers for use in 10 annealing sheet glass, and particularly to the mechanism for securing the movement of the glass. The invention has for its primary object the provision of improved means for securing an adjustment of the reciprocating bars to a common level. One 15 embodiment of the invention is illustrated in the accompanying drawings, wherein—

Figure 1 is a horizontal section through the leer operating bars with our improvement applied thereto, Fig. 2 is a half transverse section taken through the construction of Fig. 1, Fig. 3 is an enlarged sectional plan view taken at the center of the leer, Fig. 4 is an enlarged detail side elevation showing 25 the means for supporting the reciprocating bars, Fig. 5 is a plan view of one of the adjusting rods, Fig. 6 is a partial plan view of the supporting casting or bed plate, with the rollers and their supports removed therefrom, and Fig. 7 is an end elevation of one 30 of the rollers and its supporting block.

As is common in leers, our preferred structure includes a series of bars extending longitudinally of the leer, which remain at substantially the same level and are reciprocated back and forth, and sets of bars which alternate with the other bars, and have a substantially vertical movement sufficient to lift the glass off the reciprocating bars. 40 After the reciprocating bars have carried the glass forward the lifting bars lift it off the reciprocating bars and the reciprocating bars move back to a new feed position. The lifting bars then lower the glass onto the reciprocating bars and a new forward movement occurs. The means for securing these two movements is well known in the art, and the construction forms no part of my present invention which relates to the construction 45 for securing a leveling up or alining of the rollers which carry the reciprocating bars. The construction is of course applicable to leer constructions other than the particular one above described, and it will be under-

stood that the leer construction shown in 55 the drawings and hereinafter described is merely illustrative of one embodiment of the broad invention.

Referring to Figs. 1 and 2; 1, 2, 3, and 4 are the sides, top, and bottom, respectively 60 of the leer, which may be of any approved type. Mounted for an up and down movement in the leer are the lifting bars 5, such bars alternating with the reciprocating bars 6, which latter bars do not alter their vertical position. The lifting bars 5 are given their vertical movement by means of the levers 7 (Figs. 1 and 4) mounted upon transverse shafts 8. As indicated in Fig. 1 65 the levers 7 are made in pairs so as to 70 straddle the bars 5, and at periodic intervals the rods 8 are rocked, thus rocking the levers 7 and lifting and lowering the bars 5.

The reciprocating bars 6 are T-shaped in cross section as indicated in Fig. 2, and the 75 legs of the T's slide between the flanges of the rollers 9 (Fig. 7). The rollers 9 are mounted for rotation in blocks 10 having vertical guideways 11 in their sides and downwardly projecting stems 12 on their 80 lower sides. These blocks 10 are all mounted for vertical adjustment, in transversely extending bed plates 13 (Figs. 1 and 6). A bed plate extends from one side of the leer to the other and is provided with a series 85 of upstanding flanges 14 (Fig. 6). Intermediate each pair of flanges 14 is a perforation 15. The guide recesses 11 in the sides of the bearing blocks 10 (Fig. 7) are spaced apart and so proportioned as to receive the 90 flanges 14 on the bed plate, so that each bearing block is mounted for guided vertical movement. When in this position, the stem 12 on the bottom of the bearing block fits slidably through the perforation 15 in 95 the bottom of the bed plate.

Upon the bottom face of the bed plate 13 are a plurality of oblique guideways 16 (Fig. 6), such guideways being formed by the downwardly projecting opposing ribs 100 17, such ribs merging into the plate 18 (Figs. 4 and 6). Fitting in the oblique guideways 16 are the adjusting wedges 19, one of which is shown in detail in Fig. 5. These wedges are provided with handles 20 105 which are of sufficient length to extend through the casting 21 (Fig. 1) carried by the side wall of the leer. It will be seen

that the various wedges come beneath the stems 12 of the bearing blocks 10, and that by shoving the wedges inward the blocks may be adjusted vertically. It is therefore possible to adjust each of the bearing blocks independently so that the top surfaces of all the reciprocating bars 6 may be brought into horizontal alinement, and in case of warping tending to throw the bars out of alinement, the height of the blocks may be easily readjusted to bring the surfaces of the bar back into perfect alinement. Preferably, as indicated in Fig. 1, one-half of the blocks are adjusted from one side of the leer and the other half from the other side, which arrangement is more compact and does not necessitate handles of excessively great length such as would be the case if all of the blocks were adjusted from one side of the leer. At the center of the leer a curved wedge 22 is preferably employed, guided between the ribs 23 and 24, the wedge being pivoted to its handle as indicated at 25. The advantages of our construction will be readily apparent to those skilled in the art. The bearing blocks are all securely guided against lateral movement, while free to be adjusted vertically, and the vertical adjustment is secured by a positive means not liable to get out of order, and of simple and cheap construction. The adjustment, occurring as it does from the outside of the leer, can be made while the leer is in operation and in no way interfering with such operation. The bearing blocks are very securely held in their positions of adjustments, and all of the parts can be very readily assembled and disassembled.

40 What we claim is—

1. In combination in a leer having a series of reciprocating bars extending longitudinally thereof, a series of supports for the said bars independently adjustable vertically, and means operable from the outside of the leer at the side thereof whereby the supports may be separately adjusted vertically.
2. In combination in a leer having a series of reciprocating bars extending longitudinally thereof, a series of supports independently adjustable vertically for the said bars, wedges for separately adjusting

the supports vertically, and connections extending to the outside of the leer for operating the wedges separately. 55

3. In combination in a leer having a series of reciprocating bars extending longitudinally thereof, a series of supports for the said bars independently adjustable vertically provided with rollers engaging the bars, and means operable from the outside of the leer whereby the supports may be separately adjusted vertically. 60

4. In combination in a leer having a series of reciprocating bars extending longitudinally thereof, a bed plate extending transversely beneath the bars, a series of supports independently movable vertically carried by the bed plate and provided with rollers engaging the bars, a series of wedges for separately moving the supports vertically, and operating connections for moving the wedges separately, extending to the exterior of the leer. 65

5. In combination in a leer having a series of reciprocating bars extending longitudinally thereof, a series of independently movable supports for the said bars, wedges beneath the supports extending obliquely 70 with respect to the bars, and handles extending through the wall of the leer for operating the wedges separately to adjust the vertical position of the supports. 75

6. In combination in a leer having a series of reciprocating bars extending longitudinally thereof, a bed plate extending transversely beneath the bars, a series of supports independently movable vertically 80 carried by the bed plate and guided vertically thereon and provided with rollers engaging the bars, oblique guideways carried by the bed plate beneath the supports, and wedges fitting the said guideways for separately moving the supports vertically and 85 provided with handles for operating the wedges from points remote therefrom. 90

In testimony whereof we have hereunto signed our names in the presence of the two subscribed witnesses.

HERMAN S. HEICHERT.
HARRY S. DRURY.
